(21) Appl. No.: **29/758,854**

Primary Examiner — Rebekah A Caruso

(22) Filed: **Nov. 19, 2020**

(57) **CLAIM**

(51) **LOC (14) Cl. 14-99**

The ornamental design for a suction cup base for car phone holder as shown and described.

(52) **U.S. Cl.**

USPC **D14/253**; D14/253; D12/415

DESCRIPTION

(58) **Field of Classification Search**

USPC D14/251-253, 224, 224.1, 447, 451, 452; D12/114, 415, 426.1, 223; D3/218
CPC ... B60R 11/00; B60R 11/0241; B60R 11/0252; B60R 2011/0003; B60R 2011/0005; B60R 2011/0008; H04M 1/04; A45C 2011/002; A45C 2011/003; A45F 2200/0516; A45F 2200/0525
See application file for complete search history.
